UNITED STATES PATENT OFFICE

ROBERT ERROLL, OF CHICAGO, ILLINOIS

WINDOW

Application filed January 7, 1929. Serial No. 330,701.

This invention relates to double hung sliding windows (either metal or wood) in which the sash are balanced and slide up and down and are also susceptible of a rotary movement. The principal object of the invention is the provision of novel sash supporting means whereby sliding window sash may be rotated or inverted at any point between the sill and the head of window and the reverse or outside surface of glass, etc., made accessible to persons within the room for the purpose of cleaning.

Another object is to provide means whereby either or both sash may be readily removed for the purpose of glazing, or for any other purpose. Another object is to permit the removal of the pulley stiles without otherwise disturbing the frame or the sash. Another object is the provision of means for receiving and operating window screens.

With these and other objects and advantages in view, this invention consists in a window having slidable window sash provided with swivel connections and their supports, whereby the sashes may be inverted. It further consists in a window having depressible sash guiding strips that may be depressed to thereby enable either sash to be inverted upon its supports.

It further consists in a window frame comprising a sill, head, weight boxes, weight partitions, removable channel or other sectional pulley stiles, together with sliding balanced sash, said sash being provided with swivel connections and their supports whereby the sash may be rotated or inverted. It further consists in a window having depressible sash guides and parting strip thereby enabling the sash to be rotated or inverted.

It further consists of a window in which the sliding sash are provided with pivotal mounting connections so arranged that the sash may be removed from the window without disturbing or removing the sash guides or parting strip. Another feature of the win-

dow is the possibility of inserting or removing the pulley wheels without disturbing any other part of the window.

It further consists in the several novel features of construction, arrangement and combination of parts hereinafter fully set forth and claimed.

The invention is clearly illustrated in the drawings accompanying this specification in which—

Fig. 1 is a front elevation (room side) of a window embodying a simple form of the present invention;

Fig. 2 is a vertical cross section taken on the line 2—2 of Fig. 1;

Fig. 3 is a similar view, partly broken away, and showing the lower or inside window sash inverted;

Fig. 4 is a view similar to Fig. 3 showing the upper or outside sash lowered and inverted;

Fig. 5 is a side elevation, partly in vertical section, illustrating one of the swivel connections for the sash;

Fig. 6 is a detail vertical cross section taken on the line 6—6 of Fig. 1;

Fig. 7 is a detail vertical cross section taken on the line 7—7 of Fig. 1;

Fig. 8 is a detail horizontal section taken on the line 8—8 of Fig. 1, showing the guide strips for the lower sash in full lines in depressed position, and in dotted lines in extended position, and showing the guide strips for the upper sash in extended position;

Fig. 9 is a detail vertical fragmental cross section taken on the line 9—9 of Fig. 8, showing the guide strip depressed;

Fig. 10 is a detail horizontal fragmental section illustrating the connection between the window screen and sash guide;

Fig. 11 is a perspective view, partly broken away, of a fragment of one of the sashes and its connection with the sash weight;

Fig. 12 is a detail vertical cross section taken on the line 12—12 of Fig. 8;

Fig. 13 is a detail horizontal fragmental section illustrating a certain catch employed between the sash and the carriers;

Fig. 14 is a vertical cross section taken on the line 14—14 of Fig. 1;

Fig. 15 is a detail vertical horizontal section taken on the line 15—15 of Fig. 6; and

Fig. 16 is a detail horizontal cross section taken on the line 16—16 of Fig. 15.

Referring to said drawings, which illustrate one embodiment of the present invention, the reference character 14 designates a window frame, 15 the upper window sash and 16 the lower window sash which are slidably mounted in the window frame. The window frame comprises side frame members 17, an upper stile or head 14^a and a sill 14^b. The side frame members 17 embody two spaced upright frame members 18 and 18^a (see Fig. 8) which are connected by a channel section 19 that comprises a pulley stile of the frame. Between the upright frame members 18 and 18^a and in front of the main web of the pulley stile is a recess or pocket in which is contained certain parts and mechanism as will be hereinafter explained.

The window frame may be composed of wood or metal bent up, or otherwise fabricated, into the configurations shown in Figs. 6 and 8 wherein the upright frame members 18 and 18^a are arranged to receive the channel section 19. As shown, the upright frame members 18 and 18^a are each formed of three sides and the fourth side is formed by the flanges of the pulley stile member, which flanges have laterally bent edge portions that may be screwed to the offset sides or lugs 18^x of the upright frame members 18 and 18^a, so that the flanges of the pulley stile member will be flush with the side of the upright frame member with which it engages. Preferably the pulley stile 19 is formed of two pieces joined together at the middle, as shown, which is for the purpose of facilitating the assembling of the various parts of and within the pulley stile.

The upright frame member 18 is located adjacent the inner face of the wall 20 of the room and the upright frame member 18^a is adjacent the outer face thereof. Between said upright frame member 18 and 18^a of each side frame member 17 are laterally movable guide strips 21, 22 and 23, spaced apart to form between them slideways in which the window sashes are slidably mounted. Under normal conditions, the guide strips 21, 22 and 23 project beyond the side faces of the upright frame members 18 and 18^a, as is clearly seen in the left hand portion of Fig. 8, and receive between them the edge portions of the stiles of the two sashes.

In the hollow of the pulley stile section are the metal laterally movable guide strips and parting strip 21, 22 and 23, spaced apart to accommodate the channel section slide-

ways 38 in which the sash carriers 37 for the sash are housed, and on which the sash are mounted to achieve slidable and rotary movement. Under normal conditions, the guide strips and parting strips 21, 22 and 23 project beyond the side faces of the upright frame members 18 and 18^a, as is clearly shown in the left hand portion of Fig. 8, and receive between them the edge portions of the hanging stiles of the two sashes.

The guide strips referred to are susceptible of being moved back into the vertical grooves formed by the side frame members 18 and 18^a, and the slideways or guide members 38 permit the window sash to be tilted, rotated or inverted upon their supports as will be now explained. Means are provided for retracting and extending the guide strips, which means are operable from the inside of the room, and, as shown, said means comprise a plurality of transversely extending crank shafts 24 rotatably mounted in split bearings 26 secured to the pulley stile 19 and slideways 38 and in lugs 25 secured to the side flanges of the pulley stiles.

Each crank shaft is provided with crank arms 27 arranged in pairs, one pair for each guide strip and the crank arms of each pair are connected by a wrist pin 28 to which is connected an arm or link 29, the other end of which is pivotally connected to a bracket 30 secured to the rear side of each guide and parting strip 21, 22 and 23. Each pair of crank arms 27, crank shaft 24 and link 29, together with their connections with the side frame members and guide strips, form toggle joint connections whereby said guide strips may be moved into or out of the vertical pockets or grooves by rotating the crank shafts upon their axes. The crank shafts between the sill and head of the frame of the window at each side thereof are connected by a link 31 (see Fig. 12) in order to impart movement to the guide strips along parallel lines when the crank shafts are actuated.

For certain purposes, there are upper and lower crank shafts and toggle joint connections on each side of the window for each sash with a link 31 between, and the upper and lower links 31 may be detachably connected together by a pin and slot connection 32^a (see Fig. 12) whereby the two links may be disconnected, if desired. It may be found desirable to form the upper and lower portions of the pulley stiles in two sections 19^a and 19^b (see Fig. 14) joined approximately midway between the top and bottom of the window in order to permit access to the pulley weight pockets. By making the pulley stile in sections, the lower one, together with the parts carried thereby, may be removed without disturbing the upper one. This is made possible with the use of the jointed links 31 above described.

As seen in Figs. 8 and 12, one end portion

- of each crank shaft 24 is provided with a crank arm 32 extending parallel with the crank arms 27, and the link 31 pivotally connects the ends of said crank arms 32. The 5 crank shafts 24, together with their toggle joint connections with the guide strips, are concealed in the vertical pockets or grooves and behind the guide strips and window sash, and a key or crank 33 is provided which has 10 a stem 34 that may be inserted through the opening in the front of each side frame member 17 for engagement with the ends of the lower crank shafts. The stem 34 has a non-circular socket 35 upon its inner end 15 which engages over a correspondingly shaped end part 36 of each lower crank shaft. It will be observed that by engaging the stem 34 with the crank shaft, the latter may be rotated and the guide strips moved into 20 the pockets or out of them as desired, and by reason of the link connection between the upper and lower crank shafts, both crank shafts are moved in unison, thereby projecting the guide strips forward and back along 25 parallel lines.
- The sashes are rotatively mounted or swiveled upon the sash carriers 37 which are of approximately the same depth as a window sash, and said sash carriers are slidably 30 guided in slideways formed by the channel shaped slideways or guide members 38, interposed between the guide strips 21, 22 and 23. The channel shaped slideways or guide members 38 are contained in the hollow of 35 the channel section pulley stile 19 between the frame members 18 and 18^a and are rigidly mounted upon the pulley stile 19 by struts 39, spot welded or otherwise secured to the pulley stile and guide members 38. 40 The side flanges of the channel shaped guide members 38 are formed with overhanging edge portions 40 that enter grooves formed in the corner portions of the sash carriers 37, whereby said carriers are retained in the 45 channel shaped guide members against accidental disconnection therefrom.
- The sash fit loosely between the channel section slideways or guide members 38 and are rotatably mounted on the sash carriers 50 37 therein by means of sliding pins or stud shafts 41 slidably contained in housing or bearing blocks 42, spot welded or otherwise rigidly secured in the stiles of the sash. The pins or stud shafts 41 on which the sash rotates are movable into socketblocks 43, spot welded or otherwise rigidly secured in the sash carriers 37 at a point approximately 55 midway between the top and bottom of the same or at any other point determined upon. 60 To permit the sash to be completely removed from the sash carriers, the pins or stud shafts 41 may be retracted or withdrawn from the socket blocks 43, and, for this purpose, each pin or stud shaft is provided with a 65 rack bar 44 upon one side thereof with which meshes a pinion 45 contained in a cavity in the housing or bearing block 42 and mounted upon a spindle 46, which is journaled in the housing 42 and is accessible from the side of the stile of the sash where it may be provided with a slotted end for the reception of a screw driver or other tool by which the pinion may be partially rotated to withdraw or retract the pin or stud shaft 41 from the socket block 43 and thereby permit the sash to be removed from the sash carrier. The sash carriers 37 provide the sliding connection between the sashes and the slideways or guide members 38 and the guide strips 21, 22 and 23 serve somewhat in the nature 70 of window strips and parting strips for the sashes.
- Sash weights 47 are provided for each sash and are connected thereto by chains 48 which are trained over sash pulleys 49 mounted upon the rear side of the pulley stiles. The chains may be connected to the sash weights by suitable clips 50, as is shown in Fig. 11, and are attached to the sash carriers 37 by anchoring pins 51 which are connected to the chains by clips 52 and engage in hook-like anchoring members or sockets 53, spot welded or otherwise rigidly fastened to the inner side walls of the sash carriers. 75
- Each sash pulley 49 comprises a housing 49^a (see Fig. 15) in which the pulley wheel 49^b is removably mounted whereby the wheel may be removed from the housing for any desired purpose. The slideway 38 and pulley stile have registering slots 49^c through which 80 the wheel may be removed. Conveniently the shaft 49^e of the wheel seats in sockets 49^d formed in the side walls of the housing, and said sockets lead upwards and forwards through the front wall of the housing as 85 at 49^e and notches 49^f are formed in the pulley stile and slideways or guide members 38 to permit removal of the pulley shaft and therewith the wheel from the housing. By inserting a screw driver or other 90 small instrument through the slots in the slideway and pulley stile, and under the wheel the latter may be pried up and the shaft thereof moved out through the slots 49^e and 49^f. To the parting strip 22 may 95 be secured a rubbing strip 22^a (see Fig. 8) of felt or other flexible material.
- Catches 54 are provided between each sash and the associated sash carriers (see Fig. 13) 100 which catches are intended primarily for locating the sash in alignment with the carriers whenever the sash is moved from a tilted position into one in alignment with the sash carrier. As shown, in Fig. 13, a spring pressed stud 54 is contained in each 105 sash carrier and protrudes through an opening in the face thereof in position for engagement in a recess or socket 55 formed in the edge of the associated stile. The stud 110 is provided with a head or shoulder 56 upon 115

its inner side which limits its outer movement through the opening in the sash carrier, and a spring 57 between the opposite wall of the sash carrier and the head of the stud 5 serves to yieldingly hold the stud in a projected position. Whenever the sash is swung out of alignment with the sash carrier, the stud is temporarily depressed by reason of the engagement of the inclined wall of the 10 recess or socket 55 therewith, and whenever the sash is returned to its upright position, the stud snaps into the socket or recess, thereby properly locating the sash in alignment with the sash carrier, so that the guide strips 15 may be projected across the ends of the stile of the sash.

The sash weights on each side of the window are contained in a box 58 having the usual partition 59 for spacing the two weights 20 apart, and the side and rear walls 60 of said box may, if desired, be formed separate or as a part of the upright side frame members 18 and 18^a, as is shown in Fig. 8. As a preference, the entire side and rear walls 60 of the 25 box may be formed of expanded metal or wire lath into which the mortar may be pressed when the bricks, stone, or other masonry is being laid, thus providing a weather proof joint between the wall and the window frame and room. Should the weight box be formed of expanded metal or wire lath, the entire box will be lined with some substance, 30 preferably paper, to prevent the mortar from falling within the box.

35 The upper stile or head 14^a of the window frame may be formed of sheet metal bent up into shape as shown in Fig. 6. It is preferably made hollow, and at a place directly above the lower sash is formed a recess 61 40 into which the meeting rail of the lower sash may be moved so as to provide clearance below the lower sash when moved up, whereby the upper sash when moved to its lowermost position may be inverted. The upper stile or 45 head 14^a is formed with longitudinally extending walls 62 and 63 which define the sides of the recess 61, and said walls are secured to the horizontal walls of the upper stile or head. At a point directly above the member 50 of the sash lock contained on the lower sash is an opening 64 through which said member of the sash lock may protrude when the lower sash is moved to its uppermost position and a dome shaped cap or hood 65 is provided 55 over said opening 64 to cover the same.

In the forward hollow part of the upper stile or head member is contained a shade roller 66 of conventional form upon which is wound a shade curtain 67 which extends 60 down through a slot formed in the lower wall of the stile or head. The shade roller is mounted upon the usual brackets (not shown) which are fastened to the inner face of the end walls of the upper stile or head. In 65 order to obtain access to the shade roller, the

front wall 69 of the upper stile or head 14^a is removably mounted thereon, as shown in Fig. 6, and a latch 70 is provided for lockingly connecting the wall 69 with the upper stile. 70

The sashes are preferably formed of sheet metal and are glazed as usual. The meeting rails 15^a and 16^a are formed with overlapping flanges 16^b and 15^b (see Fig. 6) which are arranged to be held in engagement with the sides of the meeting rails by a spring 16^c secured to one of the flanges and bearing against the other one. With this arrangement, a weather proof joint is provided at the meeting rails of the sash. 75

To facilitate lowering of the upper sash, a hand hold member 71 (see Fig. 6) is provided on the upper sash which may be taken hold of in drawing the sash down. As shown, the hand hold member protrudes through the bottom wall of the meeting rail of the upper sash and has a head or flange 72 upon its upper end which normally rests upon said lower wall of the meeting rail. In case the upper sash is lowered to the window sill, the hand hold member strikes the sill and is thereby moved into the hollow of the meeting rail. 80

In case it is desired to provide window screens for the window, one or more pairs of the guide strips 21 and 23 may be formed with laterally projecting ribs or beads 73 (see Fig. 10) arranged to enter grooves in the side frames 74 of the window screen 75. The guide strips 21, 22 and 23 are preferably 95 formed of metal bent up into channel formation, as seen in Fig. 10, and they fit between the side frame members 18 and 18^a and the channel shaped guide members 38. 100

If desired, two bolts, one of which is shown 105 at 76 in Fig. 8, may be secured to the upright frame members 18^a, to which bolts may be attached a rod, wire or other connection, to serve as a support for either sash when tilted upon its swivel connections with the sash carriers. When glazing the sash after the latter has been installed in the window frame, the sash may be swung back until it rests upon the rod or wire carried by the bolts 76. This arrangement provides simple 110 means for holding the sash in a convenient position to facilitate the glazing of the sash. 115

In use, each sash is capable of being raised and lowered in the manner of the ordinary sliding sash. To invert the sashes for the purpose of washing them, or for any other purpose, the guide strips 21, 22 and 23 are retracted into the pockets with the use of the key 33, thereby withdrawing the guide strips 120 from the side edges of the stiles of the sashes and leaving them free to be tilted upon their swiveled connections with the sash carriers. 125

The lower sash may then be rotated upon its swiveled connections with the associated sash carriers and thereby moved into the 130

inverted position shown in Fig. 3. It is returned to normal position by rotating it in the reverse direction until in alignment with the sash carriers. To invert the upper sash, the lower sash is raised to its uppermost position with the meeting rail thereof pushed into the recess 61 of the head of the window frame. This leaves sufficient clearance for the upper sash when lowered to a lowermost position to enable the upper sash to be inverted, as is seen in Fig. 4. To return the parts to normal position, the upper sash is swung back into alignment with its carrier after which the guide strips 21, 22 and 23 are moved back into extended position and the sash may be slid up and down in the ordinary manner.

More or less variation of the exact details of construction is possible without departing from the spirit of this invention. I desire, therefore, not to limit myself to the exact form of the construction shown and described, but intend, in the following claims, to point out all of the invention disclosed herein.

I claim:

1. In a window, the combination of a window frame having side frame members each comprising upright frame members, a pulley stile removably secured thereto and sash guiding members secured to said pulley stile between said upright frame members, spaced retractile guide strips having actuating means mounted on said pulley stiles, sash carriers slidably mounted in said sash guiding members, and a window sash having swivel connections with said sash carriers and guided to move vertically between said retractile guide strips.

2. In a window, the combination of a window frame having side members, each comprising upright frame members, a channel shaped pulley stile, and spaced apart sash guiding members secured to said pulley stile in spaced relation to said upright frame members, retractile guide strips contained in the intervening spaces between the upright frame members and having retracting means mounted on said pulley stile, said pulley stile being removably secured to the upright frame members whereby the pulley stile and parts carried thereby may be moved from the remainder of the side frame member, sash carriers slidably mounted in said sash guiding members, and a window sash having swivel connections with said sash carriers and guided to move vertically between said retractile guide strips.

3. In a window, the combination of a window frame having side frame members, each comprising upright frame members, a pulley stile removably secured thereto, and guide members for the sash rigidly mounted on said pulley stile, retractile guide strips, one on each side of each guide member, means

carried by each pulley stile for retracting the guide strip adjacent each side frame member, sash carriers slidably mounted in said guide members, and a window sash having swivel connections with said sash carriers and guided to move vertically between said guide members.

4. In a window, the combination of a window frame having side frame members, each comprising upright frame members, a channel shaped pulley stile removably secured thereto, and guide members for the window sash rigidly secured to said pulley stile, retractile channel shaped guide strips, one on each side of each guide member, crank shafts, one rotatably mounted in each side frame member, toggle joint connections between said crank shaft and the adjacent guide strips adapted to be housed in said guide strips, sash carriers slidably mounted in said guide members, and a window sash having swivel connections with said sash carriers and guided to move vertically between said guide strips.

5. In a window, the combination of a window frame having side frame members, retractile guide strips adjacent said side frame members, upper and lower crank shafts journaled in each side frame member, toggle lever connections between said crank shafts and the adjacent guide strips, parallel movement means between the upper and lower crank shafts at each side of the window frame, oppositely disposed sash carriers slidably mounted between said guide strips, and a window sash having swiveled connections with said sash carriers.

6. In a window, the combination of a window frame having side frame members, each comprising a removable pulley stile and channel shaped guide members for the sash rigidly secured to the pulley stile, retractile guide strips one at each side of each guide member, upper and lower crank shafts rotatably mounted on each pulley stile, toggle joint connections between said crank shafts and the adjacent guide strips, parallel movement means between the upper and lower toggle joint connections, sash carriers slidably guided in said guide members, and window sash having swivel connections with said sash carriers and guided to move vertically between said guide strips.

7. In a window, the combination of upper and lower sashes, vertically guided sash carriers therefor, said sashes having swivel connections with their respective sash carriers, a window frame in which said sash carriers are guided, the upper stile of said window frame having a recess therein adapted for the reception of the meeting rail of the lower sash when the latter is moved to its uppermost position, and there being a covered aperture in the upper wall of said recess adapted

for the reception of a member of a sash lock on the lower sash.

8. In a window, the combination of a window frame having side frame members, each comprising a removable channel shaped pulley stile and channel shaped guide members secured to said pulley stile, retractable guide strips having actuating means carried by said pulley stiles, sash carriers slidably guided in said guide members, reversible window sash having swivel connections with said sash carriers and guided to move vertically between said guide strips, and a latch device between each sash carrier and an associated window sash.

9. In a window, the combination of a window frame having side frame members, each comprising a channel shaped pulley stile and channel shaped guide members secured thereto, depressible guide members having actuating means carried by said pulley stiles, sash carriers slidably guided in said guide members, reversible window sash swiveled upon said sash carriers and guided to move vertically between said guide members, and sash weights operatively connected to said sash carriers.

10. In a window, the combination of a window frame having side frame members, each comprising a channel shaped pulley stile and channel shaped guide members secured thereto, depressible guide strips having actuating means carried by said pulley stiles, a counterweighted window sash guided to move vertically between said guide strips, sash carriers slidably guided in said guide members, and swivel connections between said window sash and sash carriers whereby said sash may be inverted thereon.

11. In a window, the combination of oppositely disposed slidably mounted sash carriers, a window sash extending between said sash carriers, and retractable pins mounted in the stiles of the window sash and rotatably mounted in said sash carriers, said pins capable of being withdrawn from the sash carriers whereby the window sash may be detached therefrom.

12. In a window, the combination of a window sash, oppositely disposed slidably mounted sash carriers, each provided with a socket block therein, retractable pins mounted in the sash and journaled in said socket blocks, and means accessible from the face of the sash for retracting said pins from the socket blocks.

13. In a window, the combination of a window sash, a pair of slidably mounted sash carriers, socket blocks mounted in said sash carriers, retractable pins mounted in the sash and journaled in said socket blocks, said pins capable of being withdrawn from said socket blocks and being provided with rack teeth upon one side, pinions mounted in said sash and meshing with said rack teeth and having

spindles accessible at the face of the window sash and provided with means whereby the pinions may be rotated.

14. In a window, the combination of a window frame having side frame members, each composed of upright frame members, a pulley stile removably secured thereto and guide members rigidly secured to the pulley stile, spaced retractable guide strips between the upright frame members and guide members, a swiveled window sash between said guide strips and having sash carriers guided in said guide members, upper and lower crank shafts rotatably mounted on each pulley stile and having toggle joint connections with the guide strips, parallel movement means connecting the upper and lower toggle joint connections at each side of the window and one of the crank shafts at each side of the window being provided with means for engagement with a hand crank.

15. In a window, oppositely disposed retractable guide strips for guiding window sash, said guide strips being formed with window screen engaging beads.

16. In a window, the combination of spaced stationary upright frame members and a channel shaped pulley stile member formed of upper and lower sections secured to said upright frame members, at least one of said sections being removably mounted thereon.

17. In a window, the combination of spaced stationary upright frame members, a channel shaped pulley stile extending between and detachably secured to said upright frame member, slideways for sash carriers secured to said pulley stile, depressible guide strips for window sash, and operating means for retracting and extending said guide strips carried by the pulley stile, said pulley stile and the parts carried thereby being removable and replaceable with respect to the upright frame members.

18. In a window, the combination of spaced stationary upright frame members, a channel shaped pulley stile composed of sections at least one of which is detachably secured to said upright frame members, slideways for sash carriers secured to said pulley stile sections, depressible guide strips for guiding a window sash, and operating means for retracting and extending said guide strips carried by said pulley stile, the operating means for one pulley stile section being conjoinable with and disjoinable from the other.

19. In a window, the combination of a window frame having removable and replaceable pulley stiles, spaced guide members and spaced retractable guide strips carried by said pulley stiles, sash carriers slidably guided in said guide members, and a window sash mounted on said sash carriers and guided for vertical movement between said guide strips.

20. In a window, a window frame having removable and replaceable channel shaped

metal pulley stiles each formed of sections united along a vertical line and also formed of upper and lower sections, in combination with upper and lower sash guiding members and retractible guide strips carried by said sections, and a reversible window sash having sash carriers guided in said sash guiding members, the retractible guide strips overlying the edge portions of the sash.

5 ¹⁰ In witness whereof, I have hereunto set my hand this 17th day of December, 1928.

ROBERT ERROLL.
